UNITED STATES PATENT OFFICE.

WILLIS M. BAUM, OF SAUGUS, CALIFORNIA.

MAIL CATCHING AND EJECTING DEVICE ON RAILROADS.

1,250,268.

Specification of Letters Patent. Patented Dec. 18, 1917.

Application filed August 19, 1916. Serial No. 115,856.

To all whom it may concern:

Be it known that I, WILLIS M. BAUM, a citizen of the United States, residing at Saugus, in the county of Los Angeles and State of California, have invented new and useful Improvements in Mail Catching and Ejecting Devices on Railroads, of which the following is a specification.

My invention relates to improvements in mail catching and ejecting devices on railroads; and the objects of my improvements are, to catch and eject the mail pouches with one and the same operation; to catch and eject the mail pouches automatically without a man having to do any of the operating or even having to watch the operation, eliminating any and all accidents which with the present catcher-arms may sometimes happen; to eliminate the strapping of the pouches in the middle allowing more mail to be carried in one pouch; to eliminate the jamming and twisting of the pouches while catching or ejecting them; to make the catching and ejecting of mail more safe for the mail clerk as well as for any by-standers on a railroad station; to provide swingably mounted catcher-doors automatically disengaging and closing as soon as a mail pouch strikes the door; to provide swingably mounted ejecting doors operating in conjunction with the catcher-doors ejecting the mail automatically as soon as the catcher-door is operated by the incoming mail; the invention consisting in the construction, combination and arrangement of devices hereafter more fully described and claimed, and illustrated in the accompanying drawing, in which—

Figure 1 is an outline of a railroad car with my device attached to it, in top view.

Fig. 2 is my swinging door in front view.

Fig. 3 is one of the supporting arms of my doors in side view.

Fig. 4 is the supporting arm of Fig. 3 in top view.

Fig. 5 is a corner of the door filling with a lock secured to it to keep the filling of the doors engaged with the supporting arms, in side view.

Fig. 6 is the top view of Fig. 5.

Fig. 7 is a horizontal section through the door filling.

Fig. 8 is the door post with supporting arms and operating levers, in top view.

Fig. 9 is the engaging pawl and engaging lever in side view.

Fig. 10 is the door-bottom in top-view, hingedly connected to the supporting arm of the door.

Fig. 11 is the end view of the door-bottom of Fig. 10.

Fig. 12 is the end view of the door bottom hanging down from the supporting arm.

Fig. 13 is the mechanism for disengaging the swinging doors, when a mail pouch strikes the door.

Fig. 14 is the side view of Fig. 13.

Fig. 15 is a slight modification of the connection between the door-post and the supporting arms, allowing the disengaging of the doors from the door-post, in top view.

Fig. 16 is the side view of Fig. 15.

Fig. 17 is a netting to be mounted near the railroad tracks, in side view.

Fig. 18 is the top view of Fig. 17.

Similar numbers refer to similar parts throughout the several views.

In Fig. 1, the outline 1 indicates a railroad car, to which my device is applied, in open (operating) position as indicated at 2, 80 and in closed position as indicated at 3. The car-doors at 4 and 5 are of usual construction, and it will easily be understood that the common doors 4 and 5 can be on the same end of the car on the opposite sides, 85 and the swinging doors 2 and 3 constituting an important feature in my device can be on the opposite sides on the other end of the car. The catcher-doors 6 as well as the ejecting-doors 7 are mounted on the vertical 90 shaft, or door-post 8. To utilize the doors of my device for observation purposes, I mount the door fillings 9 removably in the door-arms 11, see Fig. 2. In Figs. 3 and 4, the door-arms are shown as being of U 95 shaped section, but it will easily be understood that other shapes will be just as suitable. Such shapes are chosen to allow the sliding in and removing of the fillings. The fillings can be made of any suitable material, 100

in Figs. 5, 6 and 7, sheet-metal is used, of which the surfaces may be flat and smooth, or dished on the inner side of the door, as illustrated in Fig. 7. The plate 14 in Fig. 7 will naturally be the outside of the door, while the dished plate is mounted toward the inside of the door, the part 12 is curved more than the rear part 13, to catch the mail pouch and easily direct it into the railroad car. The filling is provided with a lock whereby it can be secured between two door arms, see Figs. 5 and 6, the lock-bolt 15 being operated automatically by the spring 16. A projection 17 is provided on the lock bolt 15 whereby the filling can be disengaged from the door arms. A recess 18 in the door arms, see Fig. 4, is provided to engage with the lock of the filling. The doors swinging on the door posts are constructed to pass through the outer door-openings 19 in the railroad cars, see Fig. 1, locking against the inner door-frames 20. Between the outer walls of the railroad cars and the inner frames, a hollow space is formed to receive the door-fillings when slipped out of the door-arms, the door-frames staying thus closed while the door fillings, being shifted into the hollow walls of the railroad cars, free the door-openings for observation or other purposes, as will easily be understood. The door frames are locked within the door openings of the railroad cars by the locks on the door-arms, see Figs. 3 and 4. A lock-bolt 21 is secured to the door-arm which engages with the walls of the railroad cars, a coil spring 22 operating the bolt 21 automatically, while a projection 23 on the lock-bolt is provided to disengage the bolt by hand.

The vertical shaft, or door post 8 is journaled in the boxes 24 and 25, which can be mounted at suitable places in railroad cars.

Between the lower box 24 and the lower door arm 11, the operating lever 26 is secured to the door post. In Fig. 8, this operating lever is shown in top view, showing also the engaging pawl 27 engaging with the operating lever at 28. The engaging pawl 27 is on a common shaft 29 with the engaging lever 30, as can be more clearly seen in Fig. 9, where the engaging mechanism is shown in side view. The dotted line 31 in Fig. 8 indicates the center line of the closed door, while the door arm 11 is shown in opened position. Opening the door from the closed to the opened position, the heavy spring 32 is compressed by the operating lever 26, and as the spring can be placed in such a position as to allow a further opening movement of the door to a suitable distance far enough that the engaging pawl can be engaged as shown in Fig. 8, it will easily be understood that the setting of the door is simply done by push-

ing with the hand against the door and pressing with the foot against the engaging lever 30.

It will furthermore be understood that by pulling on the ejector door 7 the device can be set also, as pushing the catcher-door or pulling on the ejecting-door causes the same motion on the device. And then it will also be understood that, instead of pushing or pulling directly on the doors, levers may be provided by which the doors can be set from a suitable place far enough away from the device to prevent any accident through untimely operation of the device.

Springs, operating lever and engaging pawl can be below the floor of the railroad car, while the engaging lever 30 can be just above the floor. Having engaged the engaging pawl 27 with the operating lever 26 at 28, the hand can be taken away from the door, as the shape of the engaging parts will keep these parts engaged and thereby the door opened until a mail pouch strikes the door. A mail pouch striking the door, will compress the heavy spring enough to allow the engaging pawl to be pulled out of engagement by the light spring 33. The operating lever thus disengaged will be operated by the heavy spring 32 to bring the door to the closed position indicated by the center line 31.

To prevent the mail pouches from being caught between the lower end of the door and the car, a bottom plate 34 is hingedly attached to the door arms 11. When the doors are opened, these bottom plates fill the space between the doors and the railroad cars as illustrated in Figs. 10 and 1, while in closed position these bottom plates hang down as illustrated in Figs. 12 and 2.

A slight modification of the door-setting device described in Fig. 8 is illustrated in Figs. 13 and 14. In Fig. 8, the setting mechanism is constructed so that the spring will still allow a slight compression, which is caused by the inrushing mail-pouch pressing against the catcher-door 6, by which the engaging pawl 27 is allowed to disengage from the operating lever 26, after which the catcher-door is free to automatically close. In Figs. 13 and 14 the device is set not to allow any further movement of the doors by the inrushing mail pouches. The mail-pouch rushing in from the front edge 35 of the catcher-door hits against a baffle plate 36, arranged along the rear edge of the door. The baffle plate is connected with the lever 37 which is pivotally mounted on the operating lever 26 at 38 in the middle of the lever 37. While the baffle plate is attached to one end of the lever 37, the other end 39 of this lever is formed to engage with the engaging pawl 27. The operating

lever 26 does not engage with the engaging pawl 27 directly, in this slightly modified construction.

A slight modification of the connection between the door-post 8 and the door-arms 11 is illustrated in Figs. 15 and 16. While a key is shown in the Figs. 3, 4, 8, 10 and 13, a pin 40 is used as a modified interlocking means between the door-post and the door-arms. In this construction, the door-arms are turnably mounted on the door-post, on which a shoulder 41 is provided for a support of the arms.

The ejecting door 7 is the straight continuation of the catcher-door on the opposite side of the door post, see Fig. 1, the catcher-door reaching up to the top of the side walls of a railroad car and terminating at the lower end at a suitable height above the platform of the railroad station so as not to endanger any person standing on the station while the train is passing with open catcher-doors; while the ejecting door reaches down to the floor of the railroad car and is only high enough to hold the usual mail ready for delivery at a certain station, see Fig. 2. The delivery of the mail is accomplished at the same time when the catcher-door is released by the inrushing mail, as both doors are secured to the same door post. From the Fig. 2 it will also be noticed that above the ejecting door and below the catcher-door there remain parts of a stationary wall, these can also be constructed in the shape of sliding doors, and, in case that the swinging doors of the device are disengaged to be used for common door openings, these slideable stationary wall sections can be shifted into the hollow walls of the railroad cars in the same manner as previously described in connection with the swinging doors.

The mail pouches ejected from the ejecting doors are caught in a netting illustrated in Figs. 17 and 18.

If the train is passing in the direction as indicated by the arrow 42 in Fig. 18, the netting will be placed at an angle as illustrated. The netting will also be placed so that the horizontal part 43 will catch the mail pouch, and while the mail pouch is rolling over the horizontal part its motion will be stopped by the sloped part 44. A rebounding of the mail pouch toward the train will be impossible in this construction, as the mail pouch will rather be thrown away from the train by the position of the sloping part of the netting.

The netting is constructed of the framework 45, which is turnably attached to a stationary pole 46. The horizontal part 43 is hingedly connected with the sloping part 44 at 47. The horizontal part being folded toward the sloping part, the whole netting

can be turned around away from the train, the framework being mounted on a wheel 65 48, to make the turning movement easier.

Having thus described my invention, I claim:

1. A device for the purpose described consisting of swingably mounted doors centrally supported and journaled thereby forming a catcher-door projecting to one side of the central support and forming also an ejecting-door projecting to the opposite side of the central support, and setting 70 means suitably attached to the doors adapted to hold the doors in operative position.

2. A device for the purpose described consisting of swingably mounted doors centrally supported and journaled forming 80 thereby a catcher-door and an ejecting door projecting at opposite sides from the supported and journaled center of the doors, and operating mechanism suitably attached to the doors adapted to release the doors by 85 the inrushing mail.

3. The combination with a railroad car of a device for catching and ejecting mail pouches consisting of a swingably mounted door supported and journaled centrally so 90 as to form a catcher-door projecting outwardly from the railroad car and also to form an ejecting door projection to the opposite side into the railroad car, and operating mechanism secured to the railroad-car 95 engaging with the doors holding the doors in operative position adapted to hold the doors in such operative position until inrushing mail releases such operating mechanism.

4. A device for the purpose described consisting of a turnably mounted door post, a mail catching door secured radially along one side of the post, a mail ejecting door secured radially to the post opposite to the 105 catching door, and setting and operating mechanism suitably attached to the device adapted to hold the doors in opened position.

5. A device for the purpose described consisting of a vertically mounted door post turnably journaled, a catcher door secured vertically to the post projecting radially from the post, an ejecting door also secured vertically to the post opposite to the catcher-door, and setting and operating mechanism suitably attached to the device allowing an automatical closing of the door by the inrushing mail pouches.

6. A mail catching and ejecting device 120 consisting of centrally supported and journaled doors having the catching door projecting in one direction and the ejecting door projecting in the opposite direction, operating means movably attached to the 125 catching door in the path of the inrushing

4
mail, setting and operating means secured to
journaled support connected with the oper-
ating means on the door.

7. In combination with a railroad car a
5 device for catching and ejecting mail
pouches consisting of catching and ejecting
doors centrally mounted on a common door
post the catching door projecting outwardly
10 from the railroad car and the ejecting door
projecting inwardly into the railroad car,
operating mechanism secured to the door
post, and locking mechanism secured to the

railroad car normally engaging with the
operating mechanism on the door post, the
operating mechanism on the door post pro- 15
jecting upwardly into the path of the in-
rushing mail pouches.

In testimony whereof I hereunto affix my
signature in the presence of two witnesses.

WILLIS M. BAUM.
